UNITED STATES PATENT OFFICE.

ADOLF NASCHER, OF NEW YORK, N. Y.

SUSPENDER-END.

SPECIFICATION forming part of Letters Patent No. 300,495, dated June 17, 1884.

Application filed January 17, 1884. (No model.)

To all whom it may concern:

Be it known that I, ADOLF NASCHER, of the city, county, and State of New York, have invented certain new and useful Improvements 5 in Suspender-Ends, of which the following is a specification.

This invention has reference to an improved suspender-end, which is made of one continuous piece of braid, into which the ring or hook 10 that forms the connection with the buckle of the suspension-strap is directly inserted, so as to dispense with the leather or other fastening of the ring to the suspender-end.

In the accompanying drawings, Figure 1 15 represents a side elevation of my improved suspender-end provided with a connecting-ring and with a suspension device for the drawers, and Fig. 2 is a side view of a suspending end with a connecting-hook.

Similar letters of reference indicate corresponding parts.

A in the drawings represents a suspender-end, which is braided in one continuous piece from button-hole to button-hole. The button-holes *a a* of the suspender-end are formed, in 25 the act of braiding, integral therewith in the usual well-known manner. The connecting ring or hook B, by which the connection is made with the buckle of the suspender-straps, 30 is connected, in the act of braiding, to the suspender-end. A direct connection of the ring or hook with the suspender-end without any leather or other fastening is thereby obtained.

When the braiding of the suspender-end has 35 reached the point where the ring or hook B is

inserted, in the act of braiding the strands or cords to form the suspender-ends, one-half of the latter is completed, or the braid formed to the point where the ring is united therewith, one or more of the strands are left sufficiently slack to form a loop, C, about equal in length 40 to half the length of the suspender-end, and then the operation of braiding is continued until the suspender-end is completed. A spring-clasp, D, or other suitable device is attached to the loop C, which serves to grasp the drawers, whereby the latter are supported by the same suspenders which support the pantaloons. The loop or loops C form an integral portion of the braided suspender-end 45 50 A, whereby the utility of the same is increased with little increase in the cost of the same.

Having thus described my invention, I claim as new and desire to secure by Letters Patent—

A suspender-end braided continuously from 55 button-hole to button-hole and provided with a connecting ring or hook inserted at an intermediate point and braided therein, in combination with a loop or loops made integral with the suspender-end and provided with a 60 fastening device at the ends to support the drawers, substantially as described.

In testimony that I claim the foregoing as my invention I have signed my name in presence of two subscribing witnesses.

ADOLF NASCHER.
